United States Patent Office.

G. M. NICKASON, OF ELLENVILLE, NEW YORK.

Letters Patent No. 98,617, dated January 4, 1870.

IMPROVEMENT IN MARKER FOR CARPENTERS.

The Schedule referred to in these Letters Patent and making part of the same.

To all whom it may concern:

Be it known that I, G. M. NICKASON, of Ellenville, in the county of Ulster, and State of New York, have invented a new and improved Marker for Carpenters, Joiners, &c.; and I do hereby declare that the following is a full, clear, and exact description thereof, which will enable others skilled in the art to make and use the same, reference being had to the accompanying drawing, forming part of this specification, in which—

Figure 1 represents a side view, partly in section, of my improved marker.

Figure 2 is a vertical transverse section of the same, taken on the plane of the line $x-x$, fig. 1.

Figure 3 is a detail front view, on a small scale, showing the marker applied to a machine.

Similar letters of reference indicate corresponding parts.

This invention relates to a new device for marking the places on window-blinds, sashes, &c., where mortises are to be cut, and has for its object to make such marking with such precision and accuracy, that a large number of bars or planks can be prepared alike, when to be used for a number of equal-sized shutters, sashes, or other articles.

The invention consists in the application and arrangement of a series longitudinally and horizontally, as well as transversely-adjustable cutters or marking-tools, fitted upon a bar, to which slight rocking, reciprocating, or rotary motion is imparted.

A, in the drawing, represents a cylindrical or other-shaped metal bar, which has a groove or rib parallel with its axis, and on which a series of sliding sleeves, B B, is fitted. These sleeves can all be adjusted in any desired position on the bar by means of set-screws *a*, that I prefer to fit with their ends into the groove of the bar, as in fig. 1.

Each sleeve has on one side a projecting block, *b*,

which has a recess on the side to receive the marking-tool C.

This tool is slotted, as in fig. 2, and is fastened to the block by means of a screw, *c*. When worn, it can be moved further out, to project the requisite distance from the bar A.

The cutting-edges of the tools C are rounded and sharpened, as shown.

The sleeves can, as aforesaid, be adjusted any suitable distance apart, and the tools can therefore be set to mark mortises of suitable width, at suitable places.

One sleeve may even be arranged to hold two tools, as in fig. 1, in which case I prefer to apply small washers, *d*, between one or both of said tools and the block *b*, so that, according to the thickness of said washers, the tools can be adjusted apart on the sleeve.

The ends of the bar A are hung horizontally or vertically, in a suitable frame. The bar can then, by suitable mechanism, be rotated, oscillated, or moved up and down, so that it will, when a bar or plank is held against it, mark the same with its tools for the required mortises.

Thus, a large quantity of material can be accurately marked, and all pieces alike, after the tools have once been adjusted in the bar.

Having thus described my invention,

What I claim as new, and desire to secure by Letters Patent, is—

The improved "blind and sash-marker" herein described, its several parts being each constructed and arranged with reference to the others, as shown and described.

G. M. NICKASON.
